United States Patent Office.

RICHARD POHL, OF PORT HURON, MICHIGAN, ASSIGNOR TO OSWALD UNGER,
OF SAME PLACE.

Letters Patent No. 77,089, dated April 21, 1868.

IMPROVED SKATE.

The Schedule referred to in these Letters Patent and making part of the same.

Know all men that I, RICHARD POHL, of Port Huron, in the county of St. Clair, and State of Michigan, have invented a new and useful Improvement in Skates; and I do declare that the following is a true and accurate description thereof, reference being had to the accompanying drawings, and to the letters of reference marked thereon, and being a part of this specification.

Figure 1 is a top view of my invention.

Figure 2 is a view of the heel-plate from the rear.

Figure 3 is a side view of my skate.

The same letters indicate like parts in each figure.

This invention consists in manufacturing a skate to be used without straps, the fastening of which to the boot can be done with but little trouble and in a short space of time.

I have succeeded in making such a skate, by which I do without the use of straps, and so arranged that when in use the weight of the wearer causes the skate to spring and hold itself firmly on the foot.

To accomplish this, I take a suitable piece of steel, which I form into the runner A, turned up, as at B, to receive the heel-plate C. The heel-plate is firmly attached, by screws, or in any other suitable manner. The forward end of the runner is bent up, as at D, and the bar E runs back sufficiently far to act as a slide upon which work the boot-clamps. G is a short lever, attached to the slide H by a suitable pin, I. This slide is fitted with a set-screw, J, by loosening or tightening which it is adjusted as required. To the ends of the lever G are attached the levers F F, by suitable pins K K, and are so placed that they cross each other under the plate L, which is attached to another slide, M, upon the bar E, and is provided with a set-screw, N, which is for the same purpose as the set-screw J. By means of the slides H and M, the gripe of the levers F may be lengthened or shortened, as occasion may require, to suit different sizes of boots. The arms or levers F are provided with sharpened hooked points for gripping the sole of the boot. These points are shown at O. The heel-plate is provided with a flange, P, and points R, to gripe or take hold of the front of the heel of the boot. S are pins by which the plate L is attached to the slide M, and are so placed as to act as stops to prevent the levers F from spreading too far.

The putting on of these skates is very simple. Place the points O against the sole of the boot, just back of the "ball" or broadest part of the boot. Then press the skate forward until the heel of the boot sets upon the heel-plate C immediately behind the flange P. Then step firmly on the skate, and the spring thereof will cause the points R of the heel-plate to catch into the heel.

To take off the skate, press it forward until points of the heel-plate are disengaged, when it will immediately drop off.

The appearance of this skate is elegant, and a pair of them suitable for a full-grown person should not weigh over one and one-quarter pound.

What I claim as my invention, and desire to secure by Letters Patent, is—

1. The construction of a skate, in substantially the form as described, that the spring of the skate will cause it to be firmly attached to the boot of the wearer.
2. The slides H and M, provided with set-screws J and N, the levers G and F, and plate L, when arranged and operating substantially as and for the purposes set forth.
3. The combination of the above-named parts with the runner A, the heel-plate C, provided with the flange P and points R, and the bar E, when constructed and operating substantially as and for the purposes described.

RICHARD POHL.
